DISPENSING DEVICE

Filed Nov. 5, 1931

UNITED STATES PATENT OFFICE

ALBERT C. GRUNWALD, OF CHICAGO, ILLINOIS

DISPENSING DEVICE

Application filed November 5, 1931. Serial No. 573,166.

This invention relates to a device for dispensing material such as powdered soap and other fluent products.

An object of the invention is to provide a device for dispensing a limited quantity only of the dispensable material upon each operation of the actuating means.

Another object is to provide such a device having means associated therewith for preventing leakage and wastage of the dispensable material.

Another object is to provide a dispenser having novel valve means associated therewith.

Another object is to provide such a device which is simple and efficient in construction and operation.

These and other objects are attained by the means described herein and disclosed in the accompanying drawing, in which:

Fig. 1 is a front elevational view of the device of this invention shown partly in cross-section and disclosing the device in a non-dispensing position.

Fig. 2 is a fragmentary view of the lower portion of the device shown partly in section and disclosing the device in a dispensing position.

Fig. 3 is a cross-sectional view taken on the line 3—3 of Fig. 1.

The dispensing device comprises a container having a body portion 1, preferably cylindrical in form, a lower portion 2 slanting inwardly of the body, and a lower portion or neck 3 of a reduced cylindrical shape. In the upper portion of the body 1 a bearing strip 4 is secured transversely of the center of said body. This strip may be provided with side flanges 26 for purposes of reinforcement. At the center of said strip is provided a transverse slot 5 which continues through one of the flanges 26 for the purposes to be described and opening upon one edge of said strip. A retaining plate 6 is removably attached upon the central portion of

strip 4 and is provided with a slot 7 adapted to extend oppositely to the slot 5 for providing the aperture 8. A push rod 9 has its upper end slidably positioned in the aperture 8, the lower end of the rod projecting outwardly of the reduced portion or neck 3 of the container and being provided with a button 10. Adjacent its upper end, the rod 9 is formed with a shoulder 11 adapted to abut the underface of strip 4 for limiting upward movement of the push rod. At the extremity of its upper end, the rod is provided with an abutment 12, such as a nut, which limits downward movement of the push rod. A coil spring 120 is positioned upon the rod 60 between the strip 4 and a wire fork member 13 secured to an intermediate portion of the rod as at 14. The spring 120 normally urges the rod to its lowermost position. The fork member 13 is adapted to stir up the contents 65 of the container upon rotation of the rod 9 on its longitudinal axis.

In the neck portion 3 of the container is positioned a pair of valve seats 15 and 16 respectively. Upper valve seat 15 may consist 70 of a circular strip attached along one edge to the inner face of neck 3 and having the body thereof bent inwardly of the container to provide the inwardly projecting valve seat shown. The lower valve seat 16 may consist 75 of a strip having one longitudinal edge secured to the inner face of neck 3 and the remainder of its body 18 formed to project inwardly of said neck to provide the lower valve seat. The bottom edge of neck 3 may be rendered smooth by curling as at 17. The free edge of the seat 16 may be further bent inwardly of the neck 3 as indicated at 19.

Upon the rod 9 are provided an upper valve 20 and a lower valve 21 adapted to cooperate with the upper and lower valve seats respectively. Both of these valves provide preferably downwardly divergent outer surfaces as shown. In addition the edge of the lower valve may be formed with a slightly 80 85 90

flared portion 22 adapted to seat snugly against the inwardly turned portion 19 of the cooperating valve seat.

Fig. 2 illustrates the normal non-dispensing position of the device of this invention. It will be seen herein that the association of the valves with their respective valve seats is such that when the lower valve 21 is sealed against the valve seat 16, the upper valve is open for permitting a limited quantity of the dispensable material to enter the space between the upper and lower valves. By reference to Fig. 2 it will be seen that when the push rod 9 is actuated upwardly, the upper valve 20 is closed for precluding downward passage of the dispensable material thereabove. It will further be seen that when the upper valve is closed, the lower valve 21 is open for permitting dispensing of the limited quantity of fluent material held between the valves as explained. It will be seen that no matter how long the push rod is held upwardly, no further dispensing of the material will be effected inasmuch as the upper valve at this time remains continuously closed. Hence it is necessary to actuate the rod successively in order to effect further dispensing whereby wastage of the material is prevented. The spring 120, as above mentioned, normally urges the push rod downwardly whereby the lower valve is held closed. The peculiar formation of the cooperating free edge portions of the valve 21 and its seat 16, is such as to effect an efficient seal against leaking of the material from the container. The top of the body portion 1 of the container may be provided with a removable lid 23 to which one end of a chain 24 may be attached, the other end of the chain being secured to the body portion of the container, or as shown, to the uppermost of a pair of support brackets 25 secured in alignment upon the body of the container and adapted to be secured to a supporting surface for holding the dispensing device in its proper vertical position.

It will be seen by reference to Fig. 3 that the push rod 9 may be moved laterally out of position for permitting removal or replacement of the spring 120 or the fork member 13. This arrangement and cooperation of the push rod and the plate 6 likewise has to do with the assembling of the dispensing device. In assembling the device, the button 10, which may have a threaded connection with the end of the push rod, may be removed from position. The rod, with the valves 20 and 21 previously secured thereon and the fork member 13 in place, may be inserted downwardly through the body portion and the neck portion of the container. The spring 120 is now positioned and depressed downwardly upon the rod 9 until the top of said rod has been slipped into the slot 5 provided in the cross strip 4. The spring is held

depressed until the retaining plate 6 and the nut or abutment 12 have been properly placed in position as indicated in Fig. 1. The valve seat 16 may now be slipped over the lower end of the rod 9 and secured in cooperating relationship with the lower valve 21 by securing said valve seat in the manner previously described and illustrated. Thereafter the button 10 may be replaced upon the rod and the dispensing device is in readiness for positioning and use.

What is claimed is:

1. A device for dispensing fluent material and comprising a container adapted for vertical positioning and composed of a cylindrical body portion, and an inwardly convergent lower portion terminating in a reduced neck, a bearing in the upper part of said body portion, a push rod passing slidably through said bearing, an abutment on the rod on each side of the bearing for limiting slidable movement of the rod, a fork member secured to and projecting outwardly of the intermediate portion of the rod and adapted to stir the contents of the container upon rotation of the rod, a pair of spaced valve seats projecting inwardly of said neck, a pair of spaced valves secured upon the rod for cooperation with said seats, the upper valve being closed by movement of the push rod to its uppermost position and opened by movement of the rod to its lowermost position, the lower valve operating simultaneously with the upper valve and in the reverse order, the upper valve when opened being adapted to permit downward passage of a limited quantity of the dispensable material into the space between said valve and the closed lower valve, the upper valve when closed being adapted to preclude downward passage of the dispensable material thereabove, the lower valve when opened being adapted to permit dispensing of the limited quantity of material held between the valves, and a compressed spring positioned upon the rod between said bearing and fork member for normally urging the rod downwardly to retain the lower valve in closed position.

2. A device for dispensing fluent material and comprising a container open at bottom, a pair of vertically-spaced inwardly-projecting valve seats adjacent the bottom, a bearing in the container, a push rod vertically slidably in said bearing and extending through the bottom of the container, abutments on the rod on opposite sides of said bearing for limiting sliding movement of the rod, a pair of spaced valves secured upon the rod for cooperation with said valve seats, the upper valve being closed by movement of the rod to its uppermost position and opened by movement of the rod to its lowermost position, the lower valve operating simultaneously in the reverse order, the upper valve when opened being adapted to permit down-

ward passage of a limited quantity of the dispensable material into the space between said valve and the closed lower valve and the upper valve when closed being adapted to pre-
5. clude downward passage of the dispensable material thereabove, the lower valve when opened being adapted to permit dispensing of the limited quantity of material held between the valves, and resilient means normally urging the rod downwardly for retaining the lower valve in the closed position.

10 In testimony whereof, I have hereunto subscribed my name this 31st day of October, 1931.
